Co-pending Application: Applicant: Britten et al., Filed: Feb. 21, 2018.

Primary Examiner — Khawaja Anwar

(74) Attorney, Agent, or Firm — Gerard J. McGowan, Jr.

(57) **CLAIM**

The appearance of a freezer lid, as shown and described.

DESCRIPTION

FIG. 1 is a perspective view of my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the figures depict unclaimed portions of the freezer lid and form no part of the claimed design.

1 Claim, 6 Drawing Sheets(56)
